BOOKMARK

Louis G. Meyers, New York, N. Y.

Application August 9, 1951, Serial No. 241,110

1 Claim. (Cl. 281—42)

1

This invention relates to book marks.

An object of this invention is to provide a book mark which is adapted to be attached by means of a clip to an edge of the cover and which includes a spring-tensioned leaf holding lever adapted to engage a selected leaf or page.

Another object of this invention is to provide a book mark which includes a leaf or page holding lever and means for pivotally supporting and mounting the lever so that it may be swung upwardly and away from the edges of the pages in order to permit free turning of the pages.

A further object of this invention is to provide a book mark which is simple in construction and can readily be made into an attractive article.

With the above and other objects in view, my invention consists in the arrangement, combination and details of construction disclosed in the drawing and specification, and then more particularly pointed out in the appended claim.

In the drawing:

Figure 1 is a plan view of a book mark constructed according to an embodiment of this invention, showing the book mark in operative position.

Figure 2 is a detail end elevation of the device, Figure 3 is an inner side elevation of the device, Figure 4 is a sectional view taken on the line

4—4 of Figure 1,

Figure 5 is a sectional view taken on the line 30 5—5 of Figure 4.

Referring to the drawing, the numeral 10 designates generally a resilient clip formed of upper and lower plates 11 and 12 respectively, which are connected together by connecting member 13. The upper plate 11 is upwardly curved as indicated at 14, at its inner edge, to facilitate the insertion of the clip about an edge of a book cover C.

An obtusely inclined plate 15 of substantially disc-shape is struck from the upper clamping jaw or plate 11, being inclined upwardly and outwardly, and plate 15 is connected with the plate 11 by means of a narrow connecting member 16. An elongated page holding lever 17 is formed with a cup-shaped housing 18 at its inner end, and housing 18 is pivotally secured to the plate 15 by means of a pivot 19.

The lever 17 is twisted slightly adjacent its outer free end, as indicated at 20, and a right angularly disposed page engaging member 21 is secured and extends from the outer end 20 of lever 17. A coil spring 22 is disposed in the housing 18 and has one end thereof secured as

2

at 23, to the plate 15. The other end of the spring 22 is secured as at 24, to the housing 18. Spring 22 is adapted to constantly urge lever 17 downwardly to a page holding position.

5 A stop lug 25 extends from the upper outer edge of plate 15 and is positioned in the path of the upward and outward swinging of lever 17 so as to limit the swinging of lever 17 to a page releasing position.

In the use and operation of this device the clip 10 is extended over an edge of the book cover C, preferably the upper edge of the cover and in this position of clip 10, plate 15 will be inclined outwardly with respect to the adjacent or upper edge of the book cover. At this time page holding member 21 will be disposed over a page of the book so as to hold the page. If the device is used on the book while the pages are being turned, lever 17 may be swung upwardly and outwardly on pivot 19, thereby swinging page holding member 21 outwardly and away from the adjacent edge of the book. Release of lever 17 will permit spring 22 to swing lever 17 downwardly to a page holding position.

20 25 I do not mean to confine myself to the exact details of construction herein disclosed but claim all variations falling within the purview of the appended claim.

What I claim is:

30 A book mark comprising a resilient clip, a circular plate struck from said clip and extending obtusely therefrom, a lever, a cup-shaped circular housing fixed to one end of said lever, means pivotally securing said housing to said plate, a page holding member extending right angularly from the other end of said lever, a coil spring in said housing secured at one end to said housing and at the other end to said plate for constantly urging said lever downwardly to page holding position, and a stop lug struck from said clip integrally with said plate projecting over said housing for limiting the upward swinging of said lever.

LOUIS G. MEYERS.
